UNITED STATES PATENT OFFICE.

FREDERIC W. POTTER, OF BROOKLYN, NEW YORK.

TURNING-MACHINE.

1,005,069.

Specification of Letters Patent.

Patented Oct. 3, 1911.

Application filed January 5, 1910. Serial No. 536,528.

To all whom it may concern:

Be it known that I, FREDERIC WILLIAM POTTER, a citizen of the United States, residing at the borough of Brooklyn, in the county of Kings and State of New York, have invented certain new and useful Improvements in Turning Machinery, of which the following is a specification, reference being had therein to the accompanying drawings.

My invention relates to improvements in turning machines and has particular reference to a machine adapted for turning wooden lasts and other objects.

In the accompanying drawings, Figure 1 is a vertical elevation partly broken away illustrating an application of my invention. Fig. 2 is a plan view of the same. Fig. 3 is an end view with part broken away. Fig. 4 is an enlarged view of part of the machine showing model and the block from which the last is to be cut in position. Fig. 5 is a side elevation of a preferred form of cutter, and Fig. 6 is an end view looking from right to left at the same.

3 is the framework of the machine having legs 3, and standards 4 and 5 within which is mounted the main shaft 6, driven by the pulley 7, or in any suitable manner. Upon this shaft is mounted the drum 8 driving the pulley 9 upon the shaft 10 by the belt 11. The main shaft 6 also carries the pulley 12 driving the worm shaft 14 carrying the pulley 13 by the belt 13² and on the extremity 35 of the main shaft 6 is also provided the pulley 15 driving the top shaft 16 by the pulley 17 through the belt 18.

The worm shaft 14 is provided with a worm 19 meshing with the gear 20 upon the bearing 21 which also carries the gear 22 engaging the rack 23 of the traveling carriage 24 which slides back and forth upon the slide 25 mounted in the main framework of the machine. This carriage is provided with the standards 27, 28 and 29.

30 is a swinging frame mounted upon the top shaft 16 and carrying the brackets 31, 32 and 33.

34 is a shaft mounted within the frame 30 and bracket 32 and carries the pulley 35 driven by the belt 36 from the pulley 37 upon said top shaft. The shaft 34 also carries the pinion 38 which meshes with the pinion 39 mounted within the frame 30 and carrying the bearing 40 in which the model last or other suitable object is placed. 41 is a center

mounted in the bracket 31 also attached to the swinging frame 30 so that the model last or other object when mounted between the center 41 and bearing 40 is rotated and at the same time is free to swing with the frame 30. The bracket 32 in which one end of the shaft 34 is mounted and which carries the pinion 42 also supports the shaft 43 having pinion 44 which serves to rotate the bearing 45 about opposite the center 46 mounted in the bracket 33. The block of wood or other material is then placed between the center 46 and the bearing 45 and rotates simultaneously with and with the same speed as the model last mounted in the opposite side of the machine.

The shaft 10 of the sliding carriage 24 has mounted on the lateral side thereof the pulley 47 which transmits the power from said shaft to the pulley 48 by the belt 49 which continues over the pulley 50 which drives the shaft 51 at the opposite end of which is mounted the cutting tool 52. While this cutter is rotating, the cutter 53 mounted upon the shaft 10 is rotating at the same time. It will be seen that the bearings of these cutters which are mounted in the standards 27, 28 and 29 do not swing with the frame 30 but are capable of reciprocation from right to left being part of the carriage 24, while the model last or other object and the blank carried upon the swinging frame 30 are capable of feeding against the cutters by gravity.

26 is a suitable adjustable bracket carrying the arm 54 having a ball 55 at the extremity thereof which lies against the surface of the model and causes the frame to oscillate in conformity with the contour or surface thereof. This regulates the position of the blank with reference to the cutters 52 and 53 so that after the carriage has moved its entire length, that is to say after the ball 55 has crossed the entire surface of the model, it will be found that the blank has been cut in exact duplication thereof.

It has been found that by using two cutters and preferably by giving them an angle of separation about as shown that a truer duplication of the model in all its refinement of detail is obtained. While the duplicate can be cut with the cutter 53 alone, the extra cutter 52 when rotating upon an axis at an angle of less than 90 degrees to the plane of rotation of the cutter 53 insures a more perfect reproduction of the model. It has

also been found preferable to adjust the center slightly above the center of the cutting tool 52. With this arrangement it has been found possible to cut lasts which cannot be 5 cut in the regular last machines.

Of course it will be understood that various modifications may be made without departing from the spirit of the invention as set forth in the claim.

10 Having described my invention, what I claim as new, and desire to secure by Letters Patent is:

A copying lathe comprising, model holding centers and centers for the work, a following lower arranged to engage the model and controlling the relation of the work to the cut-

ters in accordance to the contour of the model, a roughing cutter whose axis is substantially parallel to the axis of the work, an end thrust finishing cutter whose axis 20 is at an angle to the axis of the work and means for producing relative motion between the work and said cutters in such a direction that the roughing cutter first meets the work. 25

In testimony whereroof I affix my signature in presence of two witnesses.

FREDERIC W. POTTER.
